Primary Examiner — John R Yeh*Assistant Examiner* — Dustin Andrew Griffith(74) Attorney, Agent, or Firm — Cowan, Liebowitz & Latman, P.C.; Anastasia Zhadina(57) CLAIM

The ornamental design for a bag as shown and described.

DESCRIPTION

FIG. 1 is a front perspective view of the bag showing my design;

FIG. 2 is a front elevation view thereof;

FIG. 3 is a left side view thereof;

FIG. 4 is a rear elevation view thereof;

FIG. 5 is a right side view thereof;

FIG. 6 is a top plan view thereof; and,

FIG. 7 is a bottom view thereof.

Portions of the bag shown in broken lines are for the purpose of illustrating stitching or portions of the purse that form no part of the claimed design.
